UNITED STATES PATENT OFFICE.

JOHN R. MONOSMITH, OF ROCKFORD, ILLINOIS.

DESIGN FOR A TOY LOCOMOTIVE.

53,856.

Specification for Design.

Patented Sept. 16, 1919.

Application filed March 19, 1919. Serial No. 283,681. Term of patent 14 years.

To all whom it may concern:

Be it known that I, JOHN R. MONOSMITH, a citizen of the United States, residing at Rockford, in the county of Winnebago and State of Illinois, have invented a new, original, and ornamental Design for a Toy Locomotive, of which the following is a specification, reference being had to the accompanying drawing, forming part thereof.

In the drawing—

Figure 1 is a side elevation of a toy locomotive, showing my new design;

Fig. 2, a plan view thereof;

Fig. 3, a front elevation; and

Fig. 4, a rear elevation.

I claim:

The ornamental design for a toy locomotive, as shown.

JOHN R. MONOSMITH.
